UNITED STATES PATENT OFFICE.

ARTHUR B. BOSTWICK, OF BROOKLYN, NEW YORK.

STENCIL.

1,111,002.

Specification of Letters Patent.

Patented Sept. 22, 1914.

Application filed December 30, 1907. Serial No. 408,559.

To all whom it may concern:

Be it known that I, ARTHUR B. BOSTWICK, a citizen of the United States, and a resident of the city of Brooklyn, county of Kings, 5 and State of New York, have invented certain new and useful Improvements in Stencils.

This invention relates to stencils and the process of making same. In an ordinary 10 stencil the openings in the plate through which the color prints the line or figure would, if the line were continuous, cut the plate into pieces and the pieces would fall apart.

15 One of the objects of my invention is to produce a stencil with the separated parts held in their proper places yet the stencil when used, will print a continuous line or figure.

20 Another object of my invention is to produce a stencil by means of which intricate and artistic designs, letters, etc., may be printed and have the effect of hand painting.

Another object is to produce a stencil 25 which will print embossed letters or designs, the lines of which will be continuous.

Other objects will appear from the herein-after description.

Referring to the drawings in which the 30 same reference character represent the same part in the several views, Figure 1 is the front or the printing face of the stencil made according to my invention. Fig. 2 is a cross section on an enlarged scale taken on line 35 2 of Fig. 1, and showing the pad back of the stencil. Fig. 3 is a similar view showing the constituent parts of the stencil shown in Fig. 2, separated from each other. Fig. 4 is an enlarged face view of one word of 40 the stencil shown in Fig. 1. This figure shows in dotted lines behind the stencil, and in full lines in the opening in the stencil, means for holding the cut-out or separated portions of the word in place. Fig. 5 is an 45 enlarged rear view of that portion of the stencil shown in Fig. 4 illustrating the means for holding the parts of the word in place. Fig. 6 is a view showing the means for holding the separated portions of the 50 stencil in place when the stencil is used for embossing. Fig. 7 is a section on line 7 of Fig. 6. Fig. 8 is a view similar to Fig. 6 showing modified means for holding the separated portions of the stencil in place. Fig. 55 9 is a plan view of a modified inking means to be used in connection with the stencil

when separate colors are to be applied. Fig. 10 is a section on line 10 of Fig. 9.

On the drawing the part marked 1 represents the stencil to be used when a flat line or tone is required. This stencil is as thin as possible and preferably foil is used. 2 indicates the cut-away portions in the stencil through which ink is forced in printing. As shown, this particular stencil is made to print words and the design of a flower. 3 represents those parts of the foil which are left entirely separated from the main portion of the foil in cutting out the various figures and designs, and which if not held in place would fall out of the foil. 4 is the means for holding these cut-out portions in place. This means consists, in this instance, of a piece of fine fabric having a mesh so that the ink will flow through the same and through the openings onto the paper or other material to be printed with the stencil.

5 represents separating strips or projections to be used when the design is to be printed in different colors.

6 is a sheet of oil paper or other material through which the ink or colors will not pass, which is used to protect the pad 7 from the ink when the stencil is used.

In constructing this stencil I proceed as follows: Lead foil is temporarily fastened to a glass with an adhesive substance. The foil is then coated with wax. The letters or designs are then cut through the wax and foil to the glass. This can be done with a sharp pointed instrument such as a sewing needle. After the letters, figures or designs are thus cut, the uncut portions 3 of the body of the foil are carefully covered with shellac and then a fine thin silk fabric 4 is applied. The silk adheres to the shellacked uncut portions of the stencil. The whole is then placed in water and the adhesive material which holds the foil to the glass is softened, permitting the foil to be removed from the glass, the silk fabric holding the separated portions of the stencil in place, and the cut-away portions 2 of the stencil remain attached to the glass. Instead of using the fabric to hold these separated parts of the foil in place, I may use any other material or I may use silk threads or wires.

If only one color is to be used in such a stencil the color is applied to the back of the fabric and is pressed through the same and through the cut-out portions 2 of the stencil

onto the paper or other material to be printed. When two or more colors are to be used, I employ the divisional strips 5 to prevent the colors from mixing or running into each other. These division strips are placed back of the fabric 4 and they are made with their front edges sharp and the rear ends flaring. These division strips form pockets into which the different colored inks are placed, and said strips effectually separate one ink from the other. As above stated, the oil paper or fabric is placed on the back of these division strips so that the pad 7 will not become soiled by the ink when the pad is forced down by the press. This pad 7 is of soft material, such as thick felt, and will readily enter into the different pockets and ink divisions, and force the ink through the fabric 4 and through the openings 2 in the foil to make the impression.

In Fig. 1, as above stated, the stencil is made to print the letters as shown, and the representation of a rose. The division pieces 5 are so placed that different colored inks may be used. For example, the letters and the stem, leaves and buds of the flower are to be printed in green. The division strips 5^a and 5^b are so placed that the ink inside 30 of 5^b will print red and that portion between 5^a and 5^b will print pink. The ink between 5^c and 5^a will also print pink and that inside of 5^d will print yellow.

In Figs. 4 and 5 I have shown on a large scale the word "Roses" to more clearly illustrate certain portions of my invention. If the letters "o" and "e" of this word for instance, were cut to print a continuous line, the inside portions 3 of these letters 40 would fall out unless some means were used for holding them in position. The silk fabric glued to these cut-away portions as well as the main body of the stencil, holds them in place so that in printing, the ink 45 passes through this fabric and through the cut-out portions of the foil and prints the letters "o" and "e" as well as the letters "r", "s" and "s" in a continuous line, so that the result does not look like a stencil 50 but has the effect of hand painting or brush work.

Instead of using the division pieces 5 to confine the ink in position and prevent the different colors running into each other, I 55 have found that if I take a pad made of several thicknesses of ink absorbing material 30, as shown in Fig. 10, and divide it into several parts, 31, 32 and 33 corresponding to the colors to be printed, I can obtain good 60 results. In constructing such a pad I apply to the cut edges 34 thereof a cement and then ink the different parts of the pad with the different colors desired and reassemble the parts. The cemented edges 34 prevent the 65 ink in one section from running into the ink

in the other section, and in printing the edges will form a sharp line or division between the inks. When the pad is reassembled it is only necessary to place it in proper position behind the stencil and apply pressure when the ink will be forced out of the pad and through the cut-out portions of the stencil and leave the proper impression on the paper or material being printed.

This construction permits me to produce 75 a finer line than when the division pieces 5 are used and no undesirable breaks appear in the printing.

When it is desired to print embossed letters or designs, I use a stencil as shown in Figs. 6, 7 or 8. In this construction instead of making the stencil out of thin material, I make it out of thick material to make the plate more durable. In this construction the plate from which the stencil is formed is marked 20. The design to be printed, as here shown "A", which is marked 21 on the drawing, is cut through the plate. 22 represents the separate parts of the letter and 23 the spaces surrounding the same. 90 The separate parts are supported or secured in place to the main portion of the plate and, as shown in Figs. 6 and 7, by thin webs 24 being left integral with the body of the plate, said webs extending across the 95 spaces 23 about midway between the thickness of the plate. In using this stencil so constructed, the printing face is placed against the surface upon which the printing is to be done. The ink is then applied to the 100 back of the plate and is forced in the spaces 23. The ink fills the spaces up to the back surface of the plate, the location of the web 24 being such as to permit the ink to flow under the same and in the space on the 105 surface being printed so that no "breaks" will appear in the printing. Upon removing the stencil from the printed surface, the ink that may be on the back of the web 24 will flow off said web into the nearest 110 opening in the plate and the space 23 will be filled up completely and there will be a continuous line printed and raised substantially the thickness of the plate.

Instead of leaving the web 24 in the construction of the design, the whole design may be made by cutting the spaces 23 clear through the plate and then the separated portions 22 may be retained in position by fine threads, wires or similar means 24^a secured to the back of the plate and to suitable position on the cut-away portions 22. The plate can be used in the same manner for embossing, as shown in Fig. 6.

As many changes could be made in the 125 above construction and many apparently widely different embodiments of my invention could be made without departing from the scope thereof, I intend that all matter contained in the above description or shown 130

in the accompanying drawings shall be interpreted as illustrative and not in a limiting sense.

I desire it also to be understood that the language used in the following claims is intended to cover all of the generic and specific features of the invention herein described and all statements of the scope of the invention, which, as a matter of language, might be said to fall therebetween.

It would be well to call attention, by way of contrast, to the superiority in various points of this process over the ordinary method of cutting and printing from stencils and embossing. In the usual method of printing from a stencil a thick ink is forced through the openings by means of a stiff brush. This necessitates a strong, comparatively heavy plate to withstand the hard usage. Such a plate is not plastic, being difficult to cut, and the line does not express the designer's idea readily. Such stencil prints are invariably stiff and clumsy. The ink in my process being forced through the openings by an even pressure without disturbing the plate or subjecting it to any hard usage, a much lighter material may be used, being cut in the way described, and the line is as easily made and as responsive to the designer's idea as if it were made with a pen or brush.

In printing from the ordinary plate used in etching, embossing, etc., the ink has to be applied at every impression and the plate wiped clean. In this process enough ink can be applied to print as many as 200 impressions, and being applied to the back no wiping of the plate is necessary.

Having now described my invention, what I claim as new and desire to secure by Letters Patent is:

1. A stencil consisting of a plate having portions thereof cut away to form a design, said cut-away portions separating parts of the plate from the main portion thereof, a fabric secured on the back of the plate to hold the said separated portions in proper position in relation to the main portion of

the plate, and means to separate and confine inks or colors placed on said fabric. 50

2. A stencil consisting of a plate having portions thereof cut away to form a design, said cut-away portions separating parts of the plate from the main portion thereof, a fabric secured on the back of the plate to hold the said separated portions in proper position in relation to the main portion of the plate, means adapted to separate and confine inks or colors placed on said fabric, a non-porous strip back of said fabric, and a pad on the back of the non-porous strip. 60

3. A stencil cut out to form a continuous line separating a portion of the plate from the main part thereof, means for holding the separated portion in place, but permitting the ink to flow to form a continuous line, an ink retaining pad separated into parts corresponding to the colors to be printed, said pad being located on the back of said stencil. 65

4. In a stencil, an inked pad consisting of a series of layers of ink retaining material, said pad being cut into parts, the edges of the parts being cemented together, whereby the ink on one portion of the pad will not run into the ink on another portion of the pad. 70

5. A stencil cut to form a continuous line separating a portion of the plate from the main part thereof, means for holding the separated portion in place and so located as to be above the under surface of the plate, an ink retaining pad divided into parts corresponding to the colors to be printed, the edges of the different parts being coated with a cement or other ink resisting material, said pad being located on the back of said stencil. 85

In witness whereof I have hereunto set my hand at the city of New York, county of New York and State of New York, this twenty-sixth day of December, 1907. 90

ARTHUR B. BOSTWICK.

In presence of—

ALLAN H. FOASE,
I. R. RICHARDS.
